United States Patent Office

Des. 184,517
Patented Mar. 3, 1959

184,517

BUILDING BLOCK OR SIMILAR ARTICLE

Leon M. Fichtner, East Orange, N. J.

Application August 13, 1958, Serial No. 52,189

Term of patent 14 years

(Cl. D18—2)

Fig. 1.

Fig. 2.

Fig. 4.

Fig. 5.

Fig. 6.

Fig. 1 is a view in perspective of a building block showing my new design;

Fig. 2 is a top plan view of the same as seen in Fig. 1;

Fig. 3 is a side elevation thereof as seen in Fig. 1;

Fig. 4 is a view in elevation of the substantially concave end face of the block;

Fig. 5 is a view in elevation of the opposite substantially convex end face of the block; and

Fig. 6 is a view in elevation of the side face of the block opposite to that shown in Fig. 1.

I claim:

The ornamental design for a building block or similar article, as shown.
